Primary Examiner—Bernard Ansher*Assistant Examiner*—C. Tuttle*Attorney, Agent, or Firm*—Notaro & Michalos**[57] CLAIM**

The ornamental design for a compact disc envelope, as shown and described.

DESCRIPTION

FIG. 1 is a front elevational view of a compact disc envelope showing my new design;

FIG. 2 is a left side elevational view thereof, the side opposite being a mirror image of the side shown;

FIG. 3 is a top plan view thereof;

FIG. 4 is a bottom plan view thereof;

FIG. 5 is a front elevational view shown with the flap element in a closed position;

FIG. 6 is a left side elevational view thereof, the side opposite being a mirror image of the side shown;

FIG. 7 is a top plan view thereof;

FIG. 8 is a bottom plan view thereof;

FIG. 9 is a rear elevational view shown with the flap in a raised position;

FIG. 10 is a rear elevational view shown with the flap in a closed position; and,

FIG. 11 is a rear elevational view shown with the flap in an alternate closed position.
